UNITED STATES PATENT OFFICE.

ROBERT SCHLUMBERGER, OF ALLEGHENY, PENNSYLVANIA.

DESIGN FOR A COIL-PIPE FOR WATER-HEATERS.

SPECIFICATION forming part of Design No. 28,650, dated May 17, 1898.

Application filed January 18, 1898. Serial No. 667,113. Term of patent 14 years.

To all whom it may concern:

Be it known that I, ROBERT SCHLUMBERGER, a citizen of the United States of America, residing at Allegheny, in the county of Allegheny and State of Pennsylvania, have invented a certain new Design for Coil-Pipes for Water-Heaters, of which the following is a specification, reference being had therein to the accompanying drawings.

10 This invention relates to a certain new and original design for water-coils for water-heaters, and with reference to the drawings—

Figure 1 is a side view of my design, and Figs. 2 and 3 are end views.

15 As shown in the drawings, the leading feature of my design consists of a pipe coiled in a series of the same length and configuration

alternately right and left and enlarged at b. These coils overlap about one-half of their respective diameters, one with the other, forming ellipses and giving a fluted outline to the whole and forming at the center an octagon with concave sides.

Having fully described my design, what I claim is—

20 The design for coil-pipe for water-heaters, as herein shown and described.

25 In testimony whereof I affix my signature in the presence of two witnesses.

ROBERT SCHLUMBERGER.

Witnesses:

A. M. WILSON,
GEO. B. PARKER.
